[57] CLAIM

The ornamental design for a vehicle rooftop air conditioner housing, as shown and described.

DESCRIPTION

FIG. 1 is a side elevation view of a vehicle rooftop air conditioner housing, showing our new design, the opposite side being a mirror image of that shown.

FIG. 2 is a top plan view thereof.

FIG. 3 is a front elevation view thereof.

FIG. 4 is a rear elevation view thereof.

FIG. 5 is a side elevation view of a vehicle rooftop air conditioner housing, showing a second embodiment of our new design, the opposite side being a mirror image of that shown.

FIG. 6 is a top plan view of FIG. 5.

FIG. 7 is a front elevation view of FIG. 5.

FIG. 8 is a rear elevation view of FIG. 5.

The bottom of the two embodiments of the vehicle rooftop air conditioner housing is substantially plain and unornamented.

FIG. 1

FIG. 2

FIG. 3

FIG. 4

FIG. 5

FIG. 6

FIG. 7

FIG. 8
